CLAIM

The ornamental design for a cabinet light, as shown and described.

DESCRIPTION

FIG. 1 is a front perspective view of a first embodiment of a cabinet light illustrating our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the cabinet light in a mounted position;

FIG. 9 is a front perspective view of a second embodiment of a cabinet light illustrating our new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and,

FIG. 16 is a front perspective view of the cabinet light in a mounted position.

The broken lines in the drawings depict unclaimed subject matter only and form no part of the claimed design.
